2 SHEETS—SHEET 2.

Fig. 3.

This technical cross-sectional diagram illustrates a mechanical assembly, possibly a cylinder or pump. The diagram is divided into several sections by vertical and horizontal lines. Key components and their labels include:

- Left section: A vertical column of three circular components, each labeled with the number 33.
- Middle section: A vertical column of three circular components, each labeled with the number 31.
- Central horizontal row: Three rectangular components labeled 30, positioned between the 33 and 31 sections.
- Bottom section: A horizontal row of four circular components labeled 30, positioned below the 31 section.
- Right side: A vertical column of three rectangular components labeled 36, positioned to the right of the 31 section.
- Bottom right corner: A circular component labeled 37.
- Bottom right corner: A circular component labeled 41.
- Bottom right corner: A circular component labeled 38.
- Bottom right corner: A circular component labeled 38.
- Bottom right corner: A circular component labeled 38.
- Bottom right corner: A circular component labeled 38.

UNITED STATES PATENT OFFICE.

ERNEST H. VINCENT, OF OAKLAND, CALIFORNIA, ASSIGNOR OF ONE-HALF TO
HERMAN CHRISTENSEN, OF SUNNYVALE, CALIFORNIA.

STEAM-BOILER.

1,351,500.

Specification of Letters Patent. Patented Aug. 31, 1920.

Application filed April 3, 1919. Serial No. 287,106.

To all whom it may concern:

Be it known that I, ERNEST H. VINCENT, a citizen of the United States, residing at Oakland, in the county of Alameda and 5 State of California, have invented new and useful Improvements in Steam-Boilers, of which the following is a specification.

This invention relates to a steam boiler, and particularly pertains to a type of boiler 10 adapted to be used upon automobiles, motor truck tractors or marine work.

It is the principal object of the present invention to provide a steam boiler which is composed of a plurality of duplicate elements 15 easily assembled to form a boiler of a desired capacity and readily repaired or removed when desired; the elements of said boiler being decidedly simple in their construction and affording a boiler structure 20 from which a maximum heating efficiency may be obtained, and by which steam may be produced in an economical manner for the steam engine of an automobile, motor truck tractor or marine work.

25 The invention contemplates the use of a multiplicity of vertical heat and water tubes arranged in sets adapted to be separately removed from the structure and easily combined therewith to form a complete circulating system and to supply steam reservoirs forming a part of the boiler structure.

The invention is illustrated by way of example in the accompanying drawings in which—

35 Figure 1 is a view in front elevation and section, showing the complete boiler.

Fig. 2 is an enlarged fragmentary view in section and elevation illustrating the inter-communicating passages between the 40 boiler sections.

Fig. 3 is a view in side elevation, showing the boiler with parts broken away to more clearly disclose the telescopic arrangement of the heat and water tubes and the manner 45 in which they are assembled.

Fig. 4 is an enlarged fragmentary view, showing the assembled relation of the boiler units.

50 Fig. 5 is an enlarged view, illustrating the combined spacing and connecting thimble.

Referring to the drawings, 10 indicates a housing, here shown as rectangular in formation and providing a lower heat chamber 11 disposed beneath a boiler structure 12 55 and a super-heating chamber 13 above this

boiler. A heat inlet opening 14 communicates with the chamber 11 and an outlet opening 15 leads from the upper chamber 13, thereby providing a complete circulation of heat through the structure. 60

As shown in the drawings, the entire housing 10 is inclosed by an outer metal wall 16, while the inner walls of the housing are here shown as separated along lines 17 and 18 to permit the removal of the lower chamber 11 and the upper chamber 13 and to thereby allow ready access to the bottom of the heat structure 12 and the top thereof. Angle plates 19 are utilized to secure these wall sections together by means of bolts 20. 70

The boiler structure comprises a plurality of combined water and heat circulating units 21. One of these units is clearly shown in Fig. 1 and will be seen to comprise a lower tube 22, preferably formed of drawn 75 steel tubing and square in cross section. This tube extends outwardly through the housing and is fitted at each end with a plug 23. One of these plugs on each tube is formed with a threaded opening, into which 80 a screw plug 24 is mounted to allow the square tubes 22 to be drained. The ends of the tubes 22 extend outwardly and between horizontal angle plates 25 and 26. These angle plates are spaced in relation to each 85 other and are adapted to be clamped by bolts 27. Interposed between the bolts 27 and the ends of the tubes 26 are bars 28 which prevent the fire and heat from passing outwardly between the tubes and 90 through the sides of the housing. These bars are formed with suitable clearance openings for the screw plugs 24. It will be understood that the square tubes 22 are arranged in parallel relation to each other 95 crosswise of the housing and in this particular instance crosswise of a vehicle frame.

Through the lower wall of each tube 22 a plurality of small openings 29 are formed. These openings receive flue tubes 30 which 100 extend upwardly and pass through steam tubes 31. The steam tubes 31 are welded with their lower ends through openings 32 in the upper wall of each of the tubes 22.

As shown in Fig. 1, the tubes 30 are considerably longer than the tubes 31 and extend upwardly through upper square tubes 33 where they are suitably expanded within openings 34 formed along the upper wall 105 of the tubes 33. The steam tubes 31 extend 110

through openings 35 in the lower wall of the upper tubes 33 and are there welded. Thus it will be seen that continuous communication is established between the heat chamber 11 and a super-heating chamber 13 and at the same time communication will be established between the lower square tubes 22 and the upper square tubes 33 of each boiler unit. By the expression "boiler unit" 10 is implied the provision of a lower tube 22, an upper tube 23 and a plurality of heat and steam tubes, as particularly shown in Fig. 1.

Referring particularly to Fig. 4, it will be noted that openings 36 are formed 15 through the opposite side walls of each of the square tubes 22 and 33. These openings are adapted to receive thimble members 37 which are cylindrical and tubular and have a circumscribing collar 38 midway their 20 lengths. The thickness of the collar represents the space between the square tubes, while the cylindrical end portions are adapted to fit securely within the openings 36 and thereby establish communication between the various square tubes at the top 25 and bottom of the boiler. Due to this arrangement, all of the tubes 31 and the upper and lower square tubes will be in constant communication and a complete circulation of steam may thus be produced.

The various boiler units are held together by tie-bolts 39 extending above and below the sets of square tubes 22, as shown in Fig. 3. These bolts pass through bolting plates 35 40 resting against the opposite outer faces of the outermost boiler sections and when the bolts are tightened will insure that all of the tubes 22 will be held firmly against the shoulders 38 of the thimbles 37 without 45 leakage. The upper ends of the boiler sections are held together by bolts 41 which extend through certain of the thimbles 37 and thus detachably secure the units together.

50 Certain of the tubes 33 are formed with openings for receiving outlet pipes 42. These pipes are led to the opposite heads of steam receivers 43. In the present instance two such receivers are shown as mounted 55 upon saddles 44 and inclosed within the super-heating chamber 13. These receivers are connected by means of outlet pipes 45 which in turn are secured to a cross connection, thus establishing communication with the main supply pipe 46 and a gage pipe 47. The supply pipe 46 may, of course, be led to a suitable super-heater or may be directly led to a steam engine, if desired.

In the operation of the present invention, 60 the boiler is filled with water up substantially to the dotted line indicated in Fig. 1. This filling operation may be produced through any suitable connection, although not shown in the drawings. Heat is then

admitted to the chamber 11 through the 65 opening 14 and will pass upwardly through the heat tubes 30 and around the water tubes. A heat radiation will thus take place as this heat is directly conveyed through the tubes 32 to the body of water contained 70 within each of said tubes. Steam will thus be generated and conveyed through the pipes 42 to the receivers 43. In the event that any one of the boiler sections is to be cleaned or drained, the screw plugs 24 may 75 be instantly removed by the use of a socket wrench. When a section of the boiler is to be removed or repaired the bolts 39 and 41 are loosened and the clamping bolts 27 are unfastened.

Having thus described my invention, what I claim and desire to secure by Letters Patent is—

1. A steam boiler including a series of units each comprising a lower and an upper tube, water tubes and heat tubes therein connected to the lower and upper tubes, a housing, the ends of the lower tubes projecting outwardly beyond the housing, angle plates secured to the housing and engaged 85 with said projecting ends of the lower tubes, bars extending over the projecting ends of the tubes, and vertical bolts connected to the angle plates and extending over the bars.

2. In a steam boiler, a series of units each 90 consisting of an upper and a lower tube, water tubes and heat tubes therein connected to the upper and lower tube of each unit, means to interconnect adjacent upper and lower tubes, a housing, bars extending over 100 the ends of the lower tubes, angle plates connected to the housing and engaging the upper and lower edges of the bars, and bolts connected to the angle plates and extending over and across the outer faces of the bars. 105

3. In a steam boiler, a series of units each 110 consisting of an upper and a lower tube, water tubes and heat tubes therein connected to the upper and lower tube of each unit, means to interconnect adjacent upper and lower tubes, a housing, bars extending over the ends of the lower tubes, angle plates connected to the housing and engaging the upper and lower edges of the bars, and bolts connected to the angle plates and extending over and across the outer faces of the bars, the ends of the lower tubes having plugged 115 outlets and the bar having openings registering with the outlets to allow of access to the latter.

120 In testimony whereof I have hereunto set my hand in the presence of two subscribing witnesses.

ERNEST H. VINCENT.
